(57) **CLAIM**

The ornamental design for a skateboard bag, as shown and described.

DESCRIPTION

FIG. 1 is a perspective view of the skateboard bag my new design in a closed configuration.

FIG. 2 is an perspective view of that skateboard bag of my new design in an open configuration.

FIG. 3 is a front elevational view of thereof, as shown in FIG. 1.

FIG. 4 is a back elevational view thereof.

FIG. 5 is a right side elevational view thereof.

FIG. 6 is a left side elevational view thereof.

FIG. 7 is a top plan view thereof; and,

FIG. 8 is a bottom plan view thereof.

The broken line elements shown in FIG. 2, depicting a skateboard, represent environmental considerations, and form no part of my new design.
